Filed Sept. 21, 1970, Ser. No. 25,095

Term of patent 14 years

Int. Cl. D26—03

U.S. Cl. D48—31

FIG. 1 is a front elevational view of a light standard or similar article illustrating my new design.

FIG. 2 is a top plan view thereof.

FIG. 3 is a rear elevational view thereof, being fragmentarily shown for convenience of illustration.

FIG. 4 is an enlarged cross-sectional view taken on line 4—4 of FIG. 1.

FIG. 5 is an enlarged cross-sectional view taken on line 5—5 of FIG. 2.

FIGS. 6, 7 and 8 are enlarged cross sectional views of additional embodiments of my design, cross section being taken on the embodiment on a plane identical to line 5—5 of FIG. 3, it being understood that these embodiments differ from the first embodiment only in the cross section of the uprights.

I claim:

The lamps are shown in broken lines in FIGS. 1—3 for illustrative purposes only.

The ornamental design of a light standard or similar article, as shown and described.
